UNITED STATES PATENT OFFICE.

ROBERT L. BLANDING, OF PROVIDENCE, RHODE ISLAND.

HEATING APPARATUS.

1,160,489.

Specification of Letters Patent. Patented Nov. 16, 1915.

Application filed May 15, 1914. Serial No. 838,869.

To all whom it may concern:

Be it known that I, ROBERT L. BLANDING, citizen of the United States, and resident of the city of Providence, in the county of Providence and State of Rhode Island, have invented certain new and useful Improvements in Heating Apparatus, of which the following is a specification.

This invention relates to heating apparatus of the class more particularly adapted for use in heating dwelling houses and other buildings, and the invention has for its object to provide a casing or shell, having a coil or other heating element mounted therein, the same being located in the line of pipe between the boiler and the radiation in such a manner that all the heating fluid passing through the pipe line will come in direct contact with this element giving to it maximum heating capacity. This element is connected to a storage tank for the purpose of heating the water contained therein.

With these and other objects in view, the invention consists of certain novel features of construction, as will be more fully described and particularly pointed out in the appended claim.

In the accompanying drawings:—Figure 1—is a diagrammatical view illustrating the general arrangement of the boiler, the piping connection, the radiation and my improved heating element mounted in the line of pipe, and said element as being connected to the storage water tank. Fig. 2—is a side elevation showing the casing in section with the heating element in the form of a coil mounted therein. Fig. 3—is a plan view of the casing in section showing a coil mounted therein. Fig. 4—is an enlarged detail illustrating the threaded nipple as entering the elbow at the end of the coil with a nut binding a packing washer against the outer face of the shell to render the connection tight.

Referring to the drawing, 10 designates the boiler or heater of any of the usual steam or water types. The heated fluid passes outward through the pipe 11 and is distributed through pipes 12 and 13 to any of the usual steam using devices such as radiators 14 or the like. In this line of pipe I mount a casing or jacket 15, which is preferably a casting having a threaded opening 16 into which is screwed the main pipe 11. This casing is also provided with openings 17 and 18 on opposite sides near its upper end for

the reception of the branch pipes 12 and 13. The upper end of this casing is also preferably provided with an opening 19, which when the branch pipes are used may be closed with a plug 20, and when the branch pipes are not used a continuation of the main pipe may be connected thereto. In this casing I mount a heating element, which may be of any suitable form or construction, but for convenience I preferably make this element of a coil of pipe 21 preferably of copper or other good heat conducting material, the ends 22 and 23 of this coil are threaded and on to each is screwed an elbow of non-corroding material such as brass. In order to support this heating coil within the casing I pass two threaded nipples 24 and 25 through openings 26 and 27, respectively in the casing and screw them into the corresponding coil elbows 34 and 35. I then place packing washers 28 and 29 onto these nipples and bind the same firmly against the face of the casing by means of the nuts 30 and 31 thus rendering the connection steam or water tight. By this construction it will be seen that the coil is suspended within the casing free and clear from the walls thereof so that it is free to expand and contract with the changes of temperature, without in any way interfering with the connections, and while held in this position all of the heating fluid in passing from the boiler to the radiators, is bound to flow through the axis of the coil, and also between the convolutions of the coil, thereby imparting to the coil the maximum heating capacity. The nipple ends 24 and 25 extending from the heating element are connected by pipes 31 and 32 to the storage tank 33.

The operation of the invention may be more fully described as follows:—A feature of my invention is the provision of a unitary structure comprising a heating element connected to the storage water tank, said heating element being located within the casing which is connected in the main pipe, whereby all of the heating fluid, such as steam or hot water, in passing from the boiler to the radiation comes in direct contact with the outer surface of its different convolutions transmitting heat thereto to quickly raise and maintain the temperature of the water in the storage tank which is circulating therethrough. Then again by mounting this heating element in the pipe line heat will be transmitted thereto just so long as there is

a circulation from the boiler thereby producing a proportional temperature in the storage tank.

The features of particular advantage in the construction of my improved heating apparatus are first: the high degree of efficiency due to the positioning of the heating element in the main pipe line where all of the passing heating fluid acts upon it to heat the circulating water from the storage tank. Second:—the heating element may be constructed of a metal of maximum heat transmitting properties, such as copper or the like, and by this construction and arrangement it is permitted to expand and contract by the action of the heat and in no way affect the joints to make them leak. Third:—the casing in which the element is located is formed so as to take the place of a regular pipe fitting, that is, it may be inserted in a straight pipe line or serve the purpose of a T or elbow for receiving the branch pipe, its construction being such as not to in any way interfere with the free circulation of the steam or water passing through it. Fourth:—the cost of installing a device of this character owing to the con-

struction of the casing is reduced to the minimum.

I claim:

In a heat generating and radiating system, the combination with a generator, and a radiator system, of a casing having threaded end openings for engaging conduit sections, and oppositely disposed branch openings in the side wall for engaging conduit sections, and located nearer one end of the casing than the other, conduit sections engaging said casing, said conduit sections and said casing establishing communication between said generator and said radiator system, an auxiliary heating coil located within and extending longitudinally of said casing, and located to cause the heating medium to pass through the axis of the coil and also between the convolutions thereof, and a separate reservoir connected with said auxiliary heating coil.

In testimony whereof I affix my signature in presence of two witnesses.

ROBERT L. BLANDING.
